US0D1040625S

(12) **United States Design Patent** (10) **Patent No.:** **US D1,040,625 S**
(45) **Date of Patent:** **** Sep. 3, 2024**

(54) **TRAY**

(71) Applicant: **CASCADES CANADA ULC**, Kingsey Falls (CA)

(72) Inventor: **Paul Landry**, Monroe, NC (US)

(73) Assignee: **CASCADES CANADA ULC** (CA)

(**) Term: **15 Years**

(21) Appl. No.: **29/811,120**

(22) Filed: **Oct. 12, 2021**

(30) **Foreign Application Priority Data**

Apr. 15, 2021 (CA) ..... CA 202790

(51) **LOC (14) Cl.** **09-03**

(52) **U.S. Cl.** **D7/701**
USPC **D7/701**

(58) **Field of Classification Search**

(57) **CLAIM**

The design for a tray, as shown and described.

DESCRIPTION

FIG. 1 is a top perspective view of a tray in accordance with a first variant;

FIG. 2 is a bottom perspective view of the tray shown in FIG. 1;

FIG. 3 is a top plan view of the tray shown in FIG. 1;
FIG. 4 is a bottom view of the tray shown in FIG. 1; and,
FIG. 5 is a side elevation view of the tray shown in FIG. 1,
the other side elevation views being identical.

The broken lines depict portions of the tray that form no part of the claim.

1 Claim, 5 Drawing Sheets

US D1,040,625 S
